UNITED STATES PATENT OFFICE.

OTTO L. HERMANN, OF ST. LOUIS, MISSOURI, ASSIGNOR TO BUXTON & SKINNER PRINTING AND STATIONERY COMPANY, OF ST. LOUIS, MISSOURI, A CORPORATION OF MISSOURI.

LOOSE-LEAF BINDER.

Application filed November 4, 1926. Serial No. 146,078.

My invention relates to the hinged portion of loose leaf binders and has for its principal objects a binder in which the hinge portions are provided with spring members whereby they automatically spread apart when unlocked, and in which said hinge portions are automatically locked together in closed position and may be easily unlocked.

The invention consists principally in providing one of the hinge members with springs that bear against a portion of the other hinge member, the springs tending to force the hinge members apart to open the binder; it also consists in a resiliently actuated locking plate mounted on one hinge member and having portions adapted to interlock automatically with portions of the other hinge member when the hinge members are in closed position; it also consists in the mounting and construction of the locking device and in the construction and arrangement of the interlocking members. The invention further consists in the loose leaf binder and in the parts and combinations and arrangements of parts hereinafter described and claimed.

In the accompanying drawing, Fig. 1 is a part plan view of a loose leaf binder embodying my invention, the hinge members being shown in closed position.

Fig. 2 is a part plan view similar to Fig. 1, parts of the end portion of the hinge being shown in section, and the hinge members being shown opened or spread apart.

Fig. 3 is a fragmentary plan view looking toward the back or outside of the hinge members showing the construction and arrangement of the interlocking portions of the hinge member and locking strip,

Fig. 4 is a sectional view on the line 4—4 in Fig. 1, the parts being shown in partly opened position, and

Fig. 5 is an end view showing the hinge members fully opened.

While my invention is applicable to various constructions of loose leaf binders, it is illustrated in the drawings as being applied to a binder similar to that shown in my Patent No. 1,571,905 dated February 2, 1926.

The front cover member 1 is hingedly secured to an end piece or hinge member 2 comprising a plate of angular section. The back cover member 3 is hingedly secured to a similar hinge member 4 or end piece. The

hinge member 2 of the front cover 1 is provided with upstanding flanges 5 at the ends, each of which has along the edge an in-turned guide flange 6 in which fits the edge of an end flange member 7 secured to the other hinge member 4. Each flange 6 has a pin 8 that rides in a longitudinal slot 9 in the other end flange 7, whereby the hinge members 2 and 4 are slidably and pivotally secured together.

Secured to one hinge member, as 4, are springs 10. The end of each spring 10 extends into the slot 9 of an end flange 7 of said hinge member 4 and is adapted to fit in a notch 11 in the end of the other end flange 5 when the hinge members 2 and 4 are in closed position. The springs 10 bearing against said end flanges 5 tend to force the hinge members apart, as will be understood from an inspection of Figure 1. When the hinge members have spread apart sufficiently that the springs 10 no longer exert pressure on said end flanges 5, said springs 10 rest against stops 12 provided on the hinge member 4, such stops preventing the springs 10 from slipping out of said slots 9.

To one of the hinge members, as 2, is movably secured a locking strip 13 as by means of headed pins or rivets 14 whose body portions fit in slots 15 in the locking strip. At each end the locking strip 13 may extend through recesses 16 provided therefor in the end flanges 5, and at one end the locking strip 13 is provided with an upturned tongue portion 17 by means of which it may be operated. The locking strip 13 is resiliently held, as by means of a spring 18 secured to an end flange 5 and bearing against the inner face of said operating tongue 17.

The locking strip 13 has an offset edge portion 19 that is adapted to slip over the edge portion of the hinge member 4 to which it is not secured. Said hinge member 4 is provided with bayonet slots 20 and the edge portion of the locking strip has tongue portions 21 pressed therefrom adapted to fit in said bayonet slots. Said tongue members 21 ride over the projecting portion 22 of the walls of the bayonet slots 20 against the pressure of the spring 18 at the end of the locking strip 13 and when the end of each tongue portion clears said projecting portion 22 of the wall of a bayonet slot 20, the pressure of said spring 18 forces the tongues

21 into locked position in said bayonet slots 20, the tongues fitting over said projecting portions of the slot walls.

As appears from the foregoing description of the construction, the hinge members of the binder are automatically locked together when the parts are assembled. The parts are easily assembled in proper position. When the hinge members are completely assembled they are automatically locked by the spring-pressed locking strip. When it is desired to open the binder, pressure on the operating tongue of the locking strip releases the hinge members and the springs cause them to spread apart, thus greatly facilitating the operation of opening the binder.

The above described loose leaf binder is easy to open and close and is securely locked in closed position. Obviously numerous changes may be made without departing from the invention and I do not wish to be limited to the precise construction shown.

What I claim is:

25 1. A loose leaf binder comprising hinge members, end flanges on said hinge members resting flatwise against each other in pairs, the end flanges of each pair having a slot and pin connection with each other, springs secured to the hinge member having slotted end flanges, the end of each spring resting in one of said slots and adapted to engage the end of the other end flange and means for locking said hinge members together 35 against the pressure of said springs.

2. A loose leaf binder comprising hinge members, end flanges on said hinge members resting flatwise against each other in pairs, the end flanges of each pair having a slot and pin connection with each other, one of said hinge members having bayonet slots, a locking strip secured to the other hinge member and having tongues adapted to fit in said bayonet slots, and springs secured to the hinge member having slotted end flanges, the end of each spring resting in one of said slots and adapted to fit in a notch provided therefor in the end of the other end flange when the binder is in closed position.

slots and adapted to engage the end of the other end flange.

3. A loose leaf binder comprising hinge members, and flanges on said hinge members resting flatwise against each other in pairs, the end flanges of each pair having a slot and pin connection with each other, one of said hinge members having bayonet slots, a spring-pressed locking strip secured to the other hinge member and having tongues adapted to fit in said bayonet slots, and springs secured to the hinge member having slotted end flanges, the end of each spring resting in one of said slots and adapted to engage the end of the other end flange.

4. A loose leaf binder comprising hinge members, end flanges on said hinge members resting flatwise against each other in pairs, the end flanges of each pair having a slot and pin connection with each other, one of said hinge members having bayonet slots, a spring-pressed locking strip secured to the other hinge member and having tongues adapted to fit in said bayonet slots, and springs secured to one of said hinge members and engaging portions of the other hinge members, thereby tending to separate said hinge members.

5. A loose leaf binder comprising hinge members, end flanges on said hinge members resting flatwise against each other in pairs, the end flanges of each pair having a slot and pin connection with each other, one of said hinge members having bayonet slots, a locking strip secured to the other hinge member and having tongues adapted to fit in said bayonet slots, and springs secured to the hinge member having slotted end flanges, the end of each spring resting in one of said slots and adapted to fit in a notch provided therefor in the end of the other end flange when the binder is in closed position.

Signed at St. Louis, Missouri, this 1st day of November, 1926.

OTTO L. HERMANN.
